RECEPTACLE FILLING DEVICE

Glen W. Smith, Grinnell, Iowa

Application June 6, 1949, Serial No. 97,340

7 Claims. (Cl. 226—102)

1

This invention relates to receptacle filling machines of the type disclosed in the U. S. patent to G. E. Strandt et al., No. 1,716,869, June 11, 1929, and has more particular reference to an improved receptacle filling device for such machines which is readily adaptable for use in filling both rigid and non-rigid containers.

Conventional filling devices for glass bottles or like rigid containers include a yieldable valved fluid discharge and air vent nozzle upwardly against which the container is forced to open the valves and allow air to escape from the container and liquid to flow from a reservoir into the container, the nozzle having a resilient container sealing ring which prevents the liquid from overflowing from the container after the latter is filled, so that the quantity of liquid delivered to the container need not be measured. These conventional devices cannot be used for filling paper or like containers which are not sufficiently rigid to force the nozzle upwardly for opening the valves. If mechanical means were provided to raise the nozzle and open the valves, the container would not be sealed, and the liquid would overflow from the container unless delivered thereto in a predetermined or measured quantity. Accordingly, the type of machine provided with conventional filling devices for rigid containers has heretofore been solely used to fill rigid containers, and it has been necessary to obtain another type of machine provided with special filling devices in order to fill non-rigid containers. An example of the latter type of machine is disclosed in the U. S. Patent to J. M. Hothersall et al., No. 2,222,617, Nov. 26, 1940. This naturally required additional floor space for the other or latter type of machine and involved a considerable extra expense in purchasing the same, as well as resulting in part-time operation of both types of machines.

The primary object of the present invention is to modify the filling devices of a conventional bottle or rigid container filling machine so that the latter may be readily converted for use in filling both rigid and non-rigid containers, thereby eliminating the need for and expense of purchasing the other type of machine and the provision of extra floor space therefor, as well as permitting full-time operation of the machine by reason of the fact that the filling devices thereof have been adapted for use in filling both types of containers.

A more specific object is to modify and improve the type of filling device disclosed in U. S. Patent No. 2,171,757, A. J. Lippold, Sept. 5, 1939, so as

2

to adapt such device for use in filling both rigid and non-rigid containers.

The exact nature of the present invention, as well as other objects and features thereof, will become apparent from the following description when considered with the accompanying drawings, in which:

Figure 1 is a fragmentary vertical section through the liquid reservoir and adjacent parts of a receptacle filling machine equipped with the present device, said device being conditioned for filling non-rigid containers and being shown partly in central vertical section and partly in elevation with the valves thereof closed.

Figure 2 is a view somewhat similar to Figure 1, showing the nozzle and associated parts partly raised to the position wherein the liquid flow control valve is closed and the air vent valve is open.

Figure 3 is a similar view showing the parts fully raised with both valves open.

Figure 4 is an enlarged view showing the device as in Figure 1, with parts omitted and parts broken away.

Figure 5 is an enlarged horizontal section taken on the line 5—5 of Figure 1.

Figure 6 is a fragmentary elevational view showing the container lifter and the adjacent portion of the nozzle raising device attached thereto.

Figure 7 is an enlarged perspective view of the nozzle raising device.

Figure 8 is an enlarged perspective view of the stop device, for opening the air vent valve, which is mounted on the liquid reservoir.

Figure 9 is a view somewhat similar to Figure 3 showing the device in use for filling bottles or rigid containers, the plane of section being at a right angle to that on which Figure 3 is taken.

Referring in detail to the drawings, A indicates the conventional liquid reservoir of a container filling machine, B indicates one of the present filling devices with which said reservoir is equipped, and C indicates the usual lifter by means of which a container is raised to receive the nozzle of the filling device and to be filled with liquid from the reservoir, and by means of which the filled container is lowered for being closed and delivered from the machine.

The reservoir A is provided at the bottom with a depending liquid dispensing or outlet tube 5, and a nozzle 6 is slidable on the lower portion of said tube and yieldingly pressed downwardly by a helical compression spring 7 disposed on said tube and interposed between the bottom of the reservoir and an external flange 8 of the nozzle. A tubular standard 9 is fixed at its lower end to

the lower end of nozzle 6 and extends upwardly through the latter and the tube 5 into the lower portion of the reservoir, said standard having diametrically opposed longitudinal elongated slots 10 in its upper portion. A rotatable valve sleeve 11, provided with diametrically opposed longitudinal elongated slots 12, is snugly frictionally and rotatably fitted on the upper portion of standard 9 and has its lower portion freely slideable in the outlet tube 5. The valve sleeve 11 forms a support for an open-top measuring cup 13 fixed on the upper end thereof, and downward movement of said valve sleeve onto standard 9 is limited by stop members 14 fixed to said valve sleeve and engaged with the bottom of the reservoir when the parts of the device are in their normal lowered position.

The nozzle 6 is provided at its lower end with an internal seat 15 for a hollow conical valve head 16, which is carried by the lower end of a tubular stem 17 that extends through the standard 9 and measuring cup 13 to a point above the latter and the maximum level of liquid in the reservoir. The stem 17 has a spool-shaped head 18 releasably engaged by the slotted intermediate arms 19 of a substantially E-shaped double sheet metal spring 20. The stem 17 serves as an air vent conduit, and the valve head 16 is provided at the lower end of its bore with a seat 21 for an air control valve 22. The valve 22 is carried by a rod-like stem 23 that extends through and above the stem 17 and has a spool-shaped head 24 releasably engaged by the slotted upper arm 25 of the spring 20. The lower arm 26 of spring 20 is slotted to freely straddle the stem 17 and rest upon the measuring cup 13, and it may be provided with downturned lugs 27 engaged over the upper edge of said cup to releasably hold the spring 20 in place. Stems 23 and 17 and standard 9 are disposed in spaced concentric relation, and the cup 13 is normally submerged below the level of liquid in the reservoir so as to be filled with such liquid. The upper portion or member of spring 20 is made weaker than the lower portion thereof for a purpose which will later be made apparent.

A stop device 28 is mounted on the reservoir and includes a clamp 29 secured over the upper edge of said reservoir and having a rigid lateral arm 30 disposed above and in the path of the head 24 of stem 23. When the nozzle 6 is forced upwardly against the action of spring 7, the entire assembly of parts 9, 11, 13, 16, 17, 20, 22 and 23 is raised until the head 24 of stem 23 engages arm 30. This prevents further upward movement of valve 22 and stem 23 so that as the rest of the parts continue upward, the arm 25 of spring 20 is stopped and flexed to place the upper portion or member of spring 20 under increasing tension, at the same time unseating valve 22 to allow air to escape from the container, in which the nozzle 6 has been inserted, upwardly through the tubular stem 17. When the tension of the upper portion or member of spring 20 exceeds the strength of the lower portion or member thereof, the arms 19 of said spring and parts 16 and 17 are held against further upward movement, while arm 26 is flexed to allow further upward movement of the standard 9, valve sleeve 11 and cup 13, thereby unseating valve 16 just after cup 13 has been raised above the level of liquid in the reservoir so as to allow the measured quantity of liquid in said cup to flow therefrom through standard 9 into the container. The filled container is then lowered again for being closed and

delivered from the machine, the cup 13 being submerged to receive a new charge of liquid and the valves being closed. The operation just described is that which takes place when filling a paper or non-rigid container R as shown in Figures 1 to 3 inclusive, at which time the valve sleeve 11 is turned to close the slots 10 and 12, and a nozzle raising device D is carried by the lifter C which engages the nozzle 6 as soon as the lower end of the latter enters the top filler opening of the container. The device D may consist of a rod bent to provide a horizontal loop 31 extending laterally from the upper ends of a pair of spaced rigidly connected vertical legs 32 which extend through ears of a receptacle positioning member 33 fixed on and disposed at one side of the lifter C, and which are engaged by set screws 34 to secure the device D in proper vertically adjusted position. The lower end of nozzle 6 is reduced to provide a shoulder 35, and the loop 31 receives this end of the nozzle and engages said shoulder so as to raise said nozzle and prevent any pressure of the container against the latter as the filling operation takes place. When filling a glass bottle E or the like, the device D is removed from the lifter C, the usual resilient sealing ring 36 is placed on the reduced lower end of nozzle 6, and the valve sleeve 11 is turned to register the slots 12 with the slots 10 as shown in Figure 9. Thus, when the bottle is raised, it engages the ring 36 in the usual way to force the nozzle upwardly. As it is not necessary to measure the quantity of liquid dispensed under these conditions, the liquid is allowed to flow directly from the reservoir as usual, said liquid flowing into standard 9 through the registered slots 10 and 12.

It will of course be understood that the reservoir will be provided, as usual, with a plurality of the filling devices, as disclosed in the prior patents referred to above.

From the foregoing description, the construction, operation and advantages of the present invention will be readily understood and appreciated by those skilled in the art. Modifications and changes in details of construction are contemplated within the spirit and scope of the invention as claimed.

What is claimed as new is:

1. In a receptacle filling device, the combination, with a pair of valves one of which is centrally apertured and provided with a seat engaged by the other, of stems for the respective valves one of which is housed within the other, a yieldable fluid discharge nozzle providing a seat for the apertured valve, a spring opposing the yielding of said nozzle, and a support for the respective valve stems including a tubular standard fixed to and extending upwardly through the nozzle and having fluid outlet openings in the upper portion thereof, and a rotatable valve sleeve frictionally fitted on the upper portion of said standard and provided at its upper end with a measuring cup.

2. In a receptacle filling device, the combination with a pair of valves one of which is centrally apertured and provided with a seat engaged by the other, of stems for the respective valves one of which is housed within the other, a yieldable fluid discharge nozzle providing a seat for the apertured valve, a spring opposing the yielding of said nozzle, and a support for the respective valve stems including a tubular standard fixed to and extending upwardly through the nozzle and having fluid outlet openings in the upper

portion thereof, a rotatable valve sleeve frictionally fitted on the upper portion of said standard and provided at its upper end with a measuring cup, and spring members one removably engaging the measuring cup and the stem of the apertured valve and the other removably engaging the stems of both valves, said spring members constituting the sole means of mounting said stems from said support.

3. In a receptacle filling device, the combination with a pair of valves one of which is centrally apertured and provided with a seat engaged by the other, of stems for the respective valves one of which is housed within the other, a yieldable fluid discharge nozzle providing a seat for the apertured valve, a spring opposing the yielding of said nozzle, and a support for the respective valve stems including a tubular standard fixed to and extending upwardly through the nozzle and having fluid outlet openings in the upper portion thereof, a rotatable valve sleeve frictionally fitted on the upper portion of said standard and provided at its upper end with a measuring cup, and spring members one removably engaging the measuring cup and the stem of the apertured valve and the other removably engaging the stems of both valves, said spring members constituting the sole means of mounting said stems from said support, and a fixed stop member disposed above and engageable by the stem of said other valve for unseating the latter.

4. In a receptacle filling device, the combination with a pair of valves one of which is centrally apertured and provided with a seat engaged by the other, of stems for the respective valves one of which is housed within the other, a yieldable fluid discharge nozzle providing a seat for the apertured valve, a spring opposing the yielding of said nozzle, and a support for the respective valve stems including a tubular standard fixed to and extending upwardly through the nozzle and having fluid outlet openings in the upper portion thereof, a rotatable valve sleeve frictionally fitted on the upper portion of said standard and provided at its upper end with a measuring cup, spring members one removably engaging the measuring cup and the stem of the apertured valve and the other removably engaging the stems of both valves, said spring members constituting the sole means of mounting said stems from said support, and a fixed stop member disposed above and engageable by the stem of said other valve for unseating the latter, said one spring member being stronger than the other.

5. In a receptacle filling device, the combination with a pair of valves one of which is centrally apertured and provided with a seat engaged by the other, of stems for the respective valves one of which is housed within the other, a yieldable fluid discharge nozzle providing a seat for the apertured valve, a spring opposing the yielding of said nozzle, and a support for the respective valve stems including a tubular standard fixed to and extending upwardly through the nozzle and having fluid outlet openings in the upper portion thereof, a rotatable valve sleeve frictionally fitted on the upper portion of said standard and provided at its upper end with a measuring cup, spring members one removably engaging the measuring cup and the stem of the apertured valve and the other removably engag-

ing the stems of both valves, said spring members constituting the sole means of mounting said stems from said support, a fixed stop member disposed above and engageable by the stem of said other valve for unseating the latter, said one spring member being stronger than the other, the lower end of said nozzle being reduced to provide a shoulder and to receive a removable container sealing ring for filling a rigid container

- 10 when the valve sleeve is turned to uncover the openings of said standard, a receptacle lifter for raising a container into filling relation to said nozzle, and a raising device removably carried by said lifter and engageable with said shoulder
- 15 to raise the nozzle for filling a non-rigid container when the valve sleeve is turned to cover the openings of said standard.
6. In a receptacle filling device, the combination with a pair of valves one of which is centrally apertured and provided with a seat engaged by the other, of stems for the respective valves one of which is housed within the other, a yieldable fluid discharge nozzle providing a seat for the apertured valve, a spring opposing the yielding of said nozzle, and a support for the respective valve stems including a tubular standard fixed to and extending upwardly through the nozzle and having fluid outlet openings in the upper portion thereof, a rotatable valve sleeve frictionally fitted on the upper portion of said standard and provided at its upper end with a measuring cup, spring members one removably engaging the measuring cup and the stem of the apertured valve and the other removably engaging the stems of both valves, said spring members constituting the sole means of mounting said stems from said support, a fixed stop member disposed above and engageable by the stem of said other valve for unseating the latter, said one spring member being stronger than the other, the lower end of said nozzle being reduced to provide a shoulder and to receive a removable container sealing ring for filling a rigid container when the valve sleeve is turned to uncover the openings of said standard, a receptacle lifter for raising a container into filling relation to said nozzle, a raising device removably carried by said lifter and engageable with said shoulder to raise the nozzle for filling a non-rigid container when the valve sleeve is turned to cover the openings of said standard, and means to vertically adjust said raising device.

7. In a receptacle filling device, the combination with a pair of valves one of which is centrally apertured and provided with a seat engaged by the other, of stems for the respective valves one of which is housed within the other, a yieldable fluid discharge nozzle providing a seat for the apertured valve, a spring opposing the yielding of said nozzle, and a support for the respective valve stems including a tubular standard fixed to and extending upwardly through the nozzle and having fluid outlet openings in the upper portion thereof, a rotatable valve sleeve frictionally fitted on the upper portion of said standard and provided at its upper end with a measuring cup, and means to limit lowering of said valve sleeve.

GLEN W. SMITH.
